UNITED STATES PATENT OFFICE

BENJAMIN VICTOR AND RICHARD E. ABRAMSON, OF BRONX, NEW YORK

SAFETY DEVICE FOR GAS RANGES

Application filed January 27, 1930. Serial No. 423,869.

This invention relates to safety devices for gas ranges and more particularly to devices of this character for automatically cutting off the fuel supply when the flame at the 5 burner is extinguished accidentally.

An important object of the invention is to provide, in a manner as hereinafter set forth, a safety device for gas ranges of the aforementioned character which will function 10 automatically when the liquid contents of a container which is being heated on the range boils over with the liability of extinguishing the burner flame.

Another important object of the invention 15 is to provide a safety device for gas ranges which embodies a spring controlled valve disposed in the fuel supply pipe which is operatively associated with a gravity actuated release mechanism whereby said valve will be automatically moved to closed position 20 when the release mechanism functions.

A further important object of the invention is to provide a safety device for gas ranges 25 of the aforementioned character which embodies manually operable means for re-setting the valve in open position in an expeditious manner when it is so desired.

Still further objects of the invention are 30 to provide a safety device for gas ranges which will be simple in construction, strong, durable, efficient in its use, which will not detract in any way from the appearance of the gas range and which may be manufactured at low cost.

All of the foregoing and still further objects and advantages of the invention will 35 become apparent from a study of the following specification, taken in connection with the accompanying drawings wherein like characters of reference designate corresponding parts throughout the several views, and wherein:

Figure 1 is a view in front elevation of a 40 gas range showing a safety device therefor constructed in accordance with this invention installed thereon.

Figure 2 is a vertical cross section through 45 the automatic spring controlled cut off valve.

Figure 3 is a view in elevation of the auto-

matic cut off valve taken at right angles to Figure 2.

Figure 4 is a horizontal cross section taken substantially on the line 4-4 of Figure 3 looking in the direction of the arrows.

55

Referring to the drawings in detail, the reference character 1 designates generally a conventional gas range provided, as usual, with the burners 2 having communication with the common gas supply pipe 3 through the medium of the manually operable valve 4. The pipe 3 extends through one side of the range 1 and has communications with a suitable source of supply.

Interposed in the supply pipe 3 adjacent the outer side of the wall 5 of the range is a valve designated generally by the reference numeral 6 and comprising a casing 7 having a tapered bore 8 extending downwardly thereinto and communicating with a passage 9 of uniform diameter throughout which extends to the lower end of the casing 7. On diametrically opposite sides, the casing 7 is provided with means 10-10 to couple the threaded adjacent end of the supply pipe 3 to the valve. A tapered valve body in the form of a plug 11 is mounted for reciprocation in the bore 8 and is provided with a stem 12 which extends through the opening 9 and has mounted on its lower end a right angularly disposed latch plate 13 which, as seen to advantage in Figure 3 of the drawings, is provided adjacent one end with a transverse depression or groove 14. On its upper end, the valve 11 is provided with an integral lug 15 and a compressible coil spring 16 encircles said lug and has its lower end impinged against the valve 11 and its upper end impinged against a closure cap or plug 17 threaded into the upper end of the valve casing 7.

85

Hangers 18-18 are rigidly secured to diametrically opposite sides of the valve casing 7 at the lower end portion thereof through the medium of the screws 19 and said hangers extend downwardly on opposite sides of the latch plate 13 and are provided with inwardly offset portions 20-20 providing shoulders beneath said latch plate 13. Pivoted mounted between the inwardly offset portions 100

20—20 of the hangers 18—18 is a cam lever 21 adapted for engagement with the latch plate 13 for manually shifting the valve body 11 upwardly against the tension of the coil 5 spring 16 to open position.

At their lower ends, the hangers 18—18 are each provided with an integral, inwardly and upwardly directed arm 22 which extends through the wall 5 of the gas range 1.

10 Pivots mounted between the free ends of the arm 22 is a substantially horizontally disposed lever 23. One end of the lever 23 is disposed adjacent the valve 6, said lever extending through a suitable opening (not 15 shown) in the wall 5 of the range. The end of the lever adjacent the valve 6 has mounted thereon a roller 24 for engagement with an arcuate spring controlled latch or keeper 25 which is pivotally mounted, as at 26, on the 20 valve casing 7 and terminates in an acutely angled end portion 27 upon which is mounted a roller 28 adapted to seat in the recess or groove 14 of the latch plate 13, as illustrated to advantage in Figure 1 of the drawings. At 25 its upper end, the latch 25 is provided with an integral stop lug 29 for engagement with the roller 24 for limiting the swinging movement of the lever 23. A coil spring 30 is disposed between the upper portion of the latch 25 and 30 the valve casing 7 for normally urging said latch toward its operative position. A receptacle 31 is suspended from the opposite end portion of the lever 23 adapted to receive liquid from an inclined pan 32 removably supported in the range 1 beneath the burners 2 thereof. At its lower end, the pan 32 is provided with a discharge spout 33 disposed above the receptacle 31 in order that the liquid will be directed into said receptacle, as will be 35 apparent. Equalizing springs 34 have one end secured to the arm 22 and their opposite ends secured to the lever 23 in spaced relation on opposite sides of the pivotal supporting connection for said lever and the purpose of 40 these springs is to assist in maintaining the lever 23 in substantially horizontal inoperative position.

In operation, assuming the device to be in 50 inoperative position as illustrated in Figure 1 of the drawings, should any liquid which is being heated on the range boil over, the same will be precipitated into the pan 32 and gravitate to the lower end thereof where it will be discharged through the spout 33 into the receptacle 31. When thus weighted, the receptacle 31 will swing that end of the lever 23 downwardly and the opposite end thereof upwardly with the result that the arcuate latch 25 will be shifted against the tension of the coil spring 30 in a manner to be disengaged from the latch plate 13 and the valve 11 will be moved downwardly to closed position, as seen in Figure 2, by the coil spring 16. It should be here mentioned that the valve body 65 11 is provided with a transverse port 35

adapted to register with the bores of the connections 10—10 of the valve casing. With the valve 11 in the position seen in Figure 2, the fuel supply will be cut off and the burner 2 extinguished. When it is desired to re-open 70 the valve 6, the receptacle 31 is emptied and replaced on the arm 23. The cam lever 21 is swung in a manner to engage the latch plate 13 and force the valve body 11 upwardly to raised position against the tension of the coil 75 spring 16 and the latch 25 is permitted to return to operative position by lifting upwardly on the end of the lever 23 which supports the receptacle 31.

While the invention has been shown and described in association with a domestic gas range, it is to be understood that the same may be used in connection with any heating device or stove for which the same is found adapted.

It is believed that the many advantages of a safety device constructed in accordance with this invention will be readily understood, and although the preferred embodiment of the invention is as illustrated and described, it is to be understood that changes in the details of construction may be had which will fall within the scope of the invention as claimed.

What is claimed is:—

1. A safety device for ranges of the character described comprising a valve casing interposed in the fuel supply pipe of the range, a valve body mounted for reciprocation in the valve casing and controlling the passage therethrough, resilient means engaged with the valve body yieldingly urging the same toward closed position, a valve stem depending from the valve body and extending through the casing, a latch plate rigidly mounted on the free end of the valve stem, said latch plate provided with a transverse groove adjacent one end, an arcuate keeper pivotally mounted intermediate its end on the valve casing and having a right angularly disposed extension on one end, a roller mounted on the extension engageable in the groove of the latch plate for retaining the valve in open position, and means for rocking the keeper in a manner to disengage the same from the latch plate comprising a pivotally mounted lever having one end disposed adjacent said keeper, a roller mounted on said end engaged with the keeper, a receptacle on the other end portion of the lever, an inclined pan for the reception of liquid disposed above the receptacle and below the burners of the range and means for discharging the liquid from the pan into the receptacle in a manner to rock the lever and shift the keeper out of engagement with the latch plate.

2. A safety device for ranges of the character described comprising a valve casing interposed in the fuel supply pipe of the range,

a valve body mounted for reciprocation in the valve casing, resilient means for yieldingly urging the valve body toward its closed position, a valve stem extending from 5 the valve body through the casing, a latch plate mounted on the free end of the valve stem and having a transverse groove adjacent one end, a spring controlled arcuate latch pivotally mounted intermediate its end 10 on the valve casing and having a roller journaled thereon adapted to seat in the groove of the latch plate for retaining the valve in open position, a pair of hangers rigidly secured to the valve casing and extending 15 therefrom on opposite sides of the latch plate, a manually operable cam lever pivotally mounted between the hangers and engageable with the latch plate for shifting the valve to open position, arcuate arms ex- 20 tending at an angle from the hangers, a lever pivotally mounted intermediate its ends between the free end portions of the arm, a roller journaled on one end of the lever engageable with the latch in a manner to rock 25 the same on its pivot out of engagement with the latch plate, and means associated with the opposite end of the lever for shifting the same.

3. In combination with a gas control cock 30 having a sliding valve member movable to open and closed position, spring means acting upon said valve member to hold the same in closed position, and gravity actuating means for actuating said valve member to 35 an open position against the action of said spring means, said gravity actuating means including a pivoted arcuate shaped latch member engageable with said valve member, a fulcrumed lever provided with a roller 40 at one end for engagement with the curved side of said arcuate shaped latch member, a container supported upon the opposite end of said lever, and adapted to be disposed beneath the outlet of an overflow catch pan, 45 and resilient means for holding said lever in a set position and for permitting the combined weight of said container and overflow to actuate said lever to release said latch member whereby said spring means will 50 move said valve member to a closed position.

4. In combination with a gas control cock having a sliding valve member movable to open and closed position, spring means acting upon said valve member to hold the same 55 in closed position, and gravity actuating means for actuating said valve member to an open position against the action of said spring means, said gravity actuating means including a pivoted arcuate shaped latch member engageable with said valve member, a fulcrumed lever provided with a roller at 60 one end for engagement with the curved side of said arcuate shaped latch member, a container supported upon the opposite end of 65 said lever, and adapted to be disposed be-

neath the outlet of an overflow catch pan, and resilient means for holding said lever in a set position and for permitting the combined weight of said container and overflow to actuate said lever to release said latch 70 member whereby said spring means will move said valve member to a closed position, and an actuating lever manually operable independently of said fulcrumed lever, and engageable with said valve member to manually move the same to an open position to allow said valve member to be engaged by said arcuated shaped latch member.

In testimony whereof we affix our signatures.

BENJAMIN VICTOR.
RICHARD EDWARD ABRAMSON.
